CLAIM

The ornamental design for heating equipment, as shown and described.

DESCRIPTION

Fig. 1.1 is a top-right perspective view of heating equipment in accordance with our new design;

Fig. 1.2 is a rear elevational view thereof;

Fig. 1.3 is a top plan view thereof;

Fig. 1.4 is a left-side elevational view thereof;

Fig. 1.5 is a right-side elevational view thereof;

Fig. 1.6 is a bottom plan view thereof; and

Fig. 1.7 is a front elevational view thereof.

The broken lines depict portions of the heating equipment that form no part of the claimed design.
